(57) **CLAIM**

The ornamental design for a fishing pole holder with auger tip, as shown and described.

DESCRIPTION

FIG. 1 is a top front perspective view of a fishing pole holder with auger tip, showing my design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top elevation view thereof;

FIG. 7 is a bottom elevation view thereof; and,

FIG. 8 is an exploded a top front perspective view thereof. The broken lines shown in the drawings depict portions of the fishing pole holder with auger tip that form no part of the claimed design.

1 Claim, 7 Drawing Sheets
